THOMAS R. WHITE AND W. G. BEDFORD, OF PHILADELPHIA, PENNSYLVANIA,
ASSIGNORS TO ^{said} W. G. BEDFORD AND WIMER BEDFORD, OF NEW YORK.

Letters Patent No. 63,682, dated April 9, 1867; antedated March 29, 1867.

IMPROVED WELL-BORING APPARATUS.

The Schedule referred to in these Letters Patent and making part of the same.

TO ALL WHOM IT MAY CONCERN:

Be it known that we, T. R. WHITE and W. G. BEDFORD, of Philadelphia, Pennsylvania, have invented certain Improvements in Well-Boring Apparatus; and we do hereby declare the following to be a full, clear, and exact description of the same, reference being had to the accompanying drawing, and to the letters of reference marked thereon.

Our invention relates to apparatus for operating rock-drills, and consists of devices fully described hereafter whereby a drill is raised from and brought against the rock turned so that its position is changed at every blow and fed downward at a speed exactly proportionate to the rapidity with which the rock is cut away.

In order to enable others skilled in the art to make and use our invention, we will now proceed to describe its construction and operation. On reference to the accompanying drawing, which forms a part of this specification—

Figure 1 is a sectional view of our improved well-boring apparatus.

Figure 2, a section on the line 1-2, fig. 1.

Figure 3, a front elevation.

Figures 4, 5, and 6, detached sectional views drawn to an enlarged scale.

Figure 7, a section on the line 3-4, fig. 6.

Figure 8, a section on the line 5-6, fig. 6.

Figure 9, a section on the line 7-8, fig. 1; and

Figure 10, a diagram intended to illustrate the operation of a portion of the apparatus.

Similar letters refer to similar parts throughout the several views.

To a base-plate, A, are secured two standards, B and B', which are connected together at the top by a cross-piece, C. In the upper ends of the standards turns a shaft, D, to the outer end of which is secured a disk, E and in a groove, x, in the latter slides freely a block, F, to a pin on which is jointed the upper end of a connecting-rod, a. At the back of the disk E are hung two catches, b and b', on each of which is a lip, c, and against each catch bears a spring which tends to press the said catch inward so that its edge shall project into the slot x. On a bracket, O, at the upper end of the standard B, is a projection, d, which is bevelled at the inner side, as shown in fig. 9, for a purpose described hereafter. In a bracket, G, secured to the standard B, slides a vertical rod, H, to the upper end of which is confined a swivel, e, and to the latter is jointed the lower end of the rod a. On the under side of the swivel e is an annular ratchet, j, fig. 6, to the teeth of which is adapted a spring pawl, i, on the rod A, so that the latter can be turned only in the direction of its arrow, figs. 1 and 6. To the lower end of the rod A is connected a screw, I, which turns in a nut, G', the latter being prevented from revolving by a pin, g, which projects from the nut into a vertical slot y, in a plate, J', secured to the standard B. To the nut G a rod or tube, J, is so connected that it can revolve freely, the said rod or tube being attached to or forming a part of the drill-rod secured to the drill or cutter. On a standard secured to the base-plate A turns a bevel-wheel, K, into which gears a similar wheel, K', on the end of a shaft, D', the latter turning in the standards B B'; and through an opening in the centre of the wheel K passes the rod J, which is turned by the wheel but can slide vertically independently of the latter. On the shaft D is a cam-disk, L, in the inner face of which is an oval groove, u, and into the latter projects a pin on a rod, M, which slides in suitable guides at the inner side of the standard B, a shoulder or projection, t, at the lower end of the rod being adapted to the teeth of a ratchet-wheel, N, secured to the shaft D'. On the bracket G is a tubular projection, f, on the inner side of which are inclined projections, n n, the upper end of one projection extending over the lower end of the next, as shown in the diagram, fig. 10. Through an opening in the upper end of the rod H projects a bar, p, the lower edge of which is bevelled, as shown in fig. 6, and against the bar bears a spring, s, which tends to maintain it in the position shown in figs. 5 and 8. The parts of the machine are brought to the position shown in fig. 3; a rotary motion in the direction of its arrow is imparted to the shaft D, when the operation will be as follows:

The block F is carried by the revolution of the disk E to the position shown in fig. 1, when the lip c on the catch b will strike the inclined side of the projection d, fig. 9; the catch will be drawn back from beneath the

block F, and the latter will descend to the lower end of the slot x. As the block descends it pushes back the catch b', which, after the block reaches the limits of its downward motion, recovers its first position. On the descent of the block F the rods H and tubes and rods connected therewith will also descend until the drill is brought against the rock. As the disk E continues its revolution the rods and drill will be again raised until the catch b' is moved back, when the block F, the rods and drill will descend as before. As the shaft D revolves a vertical reciprocating motion is imparted to the rod M, the projection i on which catches in the teeth of the ratchet-wheel N, and imparts an intermittent rotary motion to the shaft D', wheels K and K', and the drill-rods, so that the drill is never brought twice in succession against the same portion of the rock. When the rod H falls the bevelled edge of the bar p will be brought against the upper inclined edge v, fig. 10, of one of the projections n, and the rod will be turned (as the bar descends in contact with the edge v) in the direction of the arrows, figs. 10 and 5, and will be held in the position to which it is turned by the spring pawl i. As the rod H rises the bar p will strike the lower inclined edge w of the next projection n', and the spring s will yield, so that the bar can move back to the position shown in dotted lines, fig. 5, without the rod being turned. When the bar is carried above the tubular projection f the spring s will force it back to the position shown in fig. 5, so that on the next descent of the rod the bar p will strike the face v of the projection n' beneath it, and the rod will thus be turned a part of a revolution in the direction of its arrow, as before. As the rod is thus turned the screw I will also be turned in the nut G', and the latter, and the rods and drill connected therewith, will be fed downward at a speed proportionate to that at which the screw is caused to revolve. When the rock is so soft that the drill sinks deeply into the same the bar p will be carried at each downward movement to the lower end of the projection, which it strikes, and will on its upward movement be carried over the next projection, as described. The nut, rods, and drill will thus be fed quickly downward. When the rock is hard, however, the drill will sink but slightly in the same, and the bar p, instead of passing directly to the lower end of a projection, will continue to strike its upper edge (descending a greater distance at each stroke) and will not be transferred to the next projection until, as the rock is cut away, the drill descends sufficiently for the bar to reach the lower end of the projection first struck, when, on its upward movement, it will be carried over the next projection, as above described. The screw I is thus turned slowly, and the nut, rods, and drill are fed but slowly downward.

It will be seen from the above description that the drill is fed downward at a speed exactly proportionate to the rapidity with which the rock is cut away. When the nut G' has been carried nearly to the lower end of the screw I, the drill-rods are detached from the nut, the latter is moved to the upper end of the screw, another section is secured in the rods, and the nut is attached to the same, when the operations proceed as before.

Without confining ourselves to the exact construction and arrangement of parts herein described, we claim as our invention, and desire to secure by Letters Patent—

1. The revolving disk E, with its slot x, and spring catches b b', or their equivalents, in combination with the sliding block F, connected to the drill-rods, and the projection d, or its equivalent, the whole being constructed and operating substantially as and for the purpose described.
2. The rod H and spring bar p, screw I, and nut G', secured to the drill-rods, in combination with the bracket G and its inclined projections n n, and the within-described operating devices, or their equivalents, the whole being constructed and arranged for joint operation substantially as specified.
3. The swivel e, with its ratchet j, in combination with the rod H and its spring pawl i, substantially as and for the purpose set forth.
4. The shaft D', its wheels N and K', in combination with the rod J, wheel K, cam-disk L, and rod M, the whole being arranged and operating substantially as described.

In testimony whereof we have signed our names to this specification in the presence of two subscribing witnesses.

THOS. R. WHITE,
W. G. BEDFORD.
